COOLING UNIT

Maxwell R. Karge, Brockport, N. Y.

Application April 16, 1932, Serial No. 605,683

7 Claims. (Cl. 62—141)

This invention relates to cooling units made up of combined refrigerating units and cooling apparatus and has for its object to so construct such combined units that their operation will secure an extremely high refrigerating efficiency.

Another object of this invention is to so construct and combine the refrigerating unit and cooling apparatus that it provides a compact cooling unit which is extremely simple to install and occupies but a minimum amount of space.

Another object of this invention is to provide the compressor of the refrigerating unit with a combined oil reservoir and oil gauge.

Another object of this invention is to so construct the mounting of the compressor of the refrigerating unit that it may be used with a reservoir which can be increased in capacity by the addition of tubular units thereto.

These and other objects will become more readily apparent from the detailed description of the invention which follows, reference being had to the accompanying drawings in which

Figure 1 is a front elevation of a combined refrigerating unit and milk cooling apparatus.

Figure 2 is a front elevation and partial section of a combined refrigerating unit and cooling apparatus of the immersion type.

Figure 3 is a front elevation of a modified form of the refrigerating unit and cooling apparatus.

Figure 4 is a front elevation of the compressor and its novel form of tank.

Figure 5 is a detail view of the crank case of the compressor and its combined oil gauge and oil reservoir.

In the several figures of the drawings like reference numerals indicate like parts.

The cooling units forming the subject matter of my present invention include modified forms of the refrigerating unit illustrated and described in my prior application Serial No. 591,550. This refrigerating unit is especially adapted for use with the cooling units in that it is simple and compact in construction and utilizes one of its members as the support for the unit and the motor drive thereof. As illustrated in Figure 1, the compressor 1 is provided with the cross shaped crank case 2, into the bottom of which is fastened the condenser 3. This condenser has a suitable floor plate at the bottom of it with which

the condenser is anchored to the base 5 of the cooler to support the compressor thereon. The compressor is driven by the electric motor 6 which is adjustably mounted on the condenser and drives the compressor by means of the belt drive 7.

Supported in the side of the cross shaped crank case 2 of the compressor and horizontally projecting from it is the evaporator 8. This evaporator extends into the cooling cabinet 9 and has the cooling fins 10, 10 mounted thereon within the cabinet. On the exposed portion of the evaporator between the compressor and the cooling cabinet are provided a pair of collars 11 and 12 which are suitably spaced from each other and encircle the perimeter of the evaporator. On these collars rests the aerator 13 of the pre-cooling water milk cooler. This aerator comprises a suitable radiator thru which cooling water is allowed to circulate while the milk flows over the front and back from the top to the bottom thereof. The cooling water enters the radiator thru the inlet 14 and leaves it thru the outlet 15 after it has absorbed some of the heat of the milk which has passed over the aerator.

Above the radiator is mounted a trough 16 in the bottom of which are provided suitable openings from which the milk is fed onto the aerator. The milk is fed into the trough from a tank 17 supported above the aerator and its flow into the trough is regulated by the faucet 18.

Below the evaporator 8 and in line with the aerator 13 is located another trough 19 which is suitably suspended from the evaporator on the outside of the collars 11 and 12 to catch the milk as it leaves the evaporator. This second trough 19 has a single outlet 20 in the middle of the bottom of it thru which the milk passes into the milk can 21 placed below the trough 19. In this way the milk from the tank 17 is first allowed to flow over the aerator for a preliminary cooling by the cooling water circulating in the aerator. The milk thus cooled is then allowed to flow onto and around the periphery of the evaporator 8 between the collars 11 and 12 to have this evaporator absorb more heat from the milk and provide a second pre-cooling for it before it enters the milk can 21 thru the trough 19 and its outlet 20.

The milk thus cooled and filled into the can is then placed in the can into the cooling cabinet 9 where the milk is finally brought to the desired low temperature by the absorption of more of its heat by the evaporator thru the cooling fins 10, 10.

A door 22 is provided at one end of the cooling cabinet to open and close the opening thru which the milk cans 21 are inserted or withdrawn from the cabinet.

In Figure 2 I have illustrated a cooling unit of the immersion type. This unit includes a suit-

able cooling tank 25 in which is contained a liquid cooling medium such as a brine solution or water. The refrigerating unit for this cooling unit is made up of the compressor 26, the horizontal condenser 27 and the evaporator 28. In this unit the horizontally arranged condenser 27 furnishes the support for the unit which, for this purpose, is provided with suitable legs or standards 29 and 30 by which the condenser is supported and anchored on top of the cooling tank 25. In place of having the condenser anchored in the side of the crank case of the compressor, its condensing water pipe 31, which extends from one end of the condenser to the other, is welded into the side of the evaporator tube to provide the mechanical connection between the condenser and the compressor 26 and surge drum 32 forming part of the evaporator 28. This method of mechanically joining the condenser to the evaporator serves to simplify the pipe connection between the water pipe 31 of the condenser and the water jacket of the compressor formed by the pipe and also serves to simplify the connection between the compressor and the condenser formed by the pipe 34, and the connection between the condenser and the evaporator formed by the pipe connection 35. The cooling water enters the condensing water pipe 31 thru the inlet 36 at the outer end of the condenser 27.

The evaporator is connected to the bottom of the crank case of the compressor 26 and the surge tank section of it extends vertically into the inside of the cooling tank 25 where it has the evaporator proper extending horizontally therefrom and has the cooling fins 38, 38 mounted thereon. The evaporator and its cooling fins absorb the heat from the cooling medium in the cooling tank and thus indirectly cool the milk cans 39 and their contents while they are partially submerged in the cooling tank as illustrated in Figure 2.

The cooling unit illustrated in Figure 3 is provided with practically the same form of cooling unit illustrated in Figure 2 except that in place of an evaporator a reservoir or liquid receiver 40 is mounted into the bottom of the crank case 41 of the compressor 42 to suitably support the compressor and one end of the condenser 43. The outer end of the condenser is supported by a standard or leg 44 and both the surge tank 40 and the standard 44 are provided with a suitable floor plate with which they are anchored to the floor or other supporting surface.

The evaporator for this unit comprises a suitable coil system 45 which is connected at one end with the reservoir or liquid receiver 40 near the bottom of it and with the intake of the compressor 42 with the other end.

In Figure 4 I have illustrated the compressor 46 in combination with a novel form of storage tank which is made up of a vertical manifold 47 which is mounted into the bottom of the crank case 48 of the compressor and is provided with a floor plate 49 with which it is anchored to the floor to support the compressor and its driving motor thereon. From the manifold 47 branches off one or more tubular tanks 50 in which the compressed air is stored therein. To increase the capacity of the storage tank it is therefore only necessary to add more tubular tanks 50 to the manifold 47 and let them project radially in any desired direction from it. If the tubular tanks are connected to the manifold parallel to each other, very little space will be occupied by

them so that the whole unit can be compactly mounted in a minimum space.

In Figure 5 I have illustrated a novel form of oil reservoir used in connection with my compressors in which the crank case has the shape of a cross member. This reservoir comprises a tubular extension 51 which is threaded into the side of the crank case 52 in line with the crank shaft which is mounted in the opposite side of the crank case. The tubular extensions may be made any length to store sufficient lubricating oil for the continued or intermittent operation of the crank 53 over a long period. The outer end of the reservoir is closed by a gauge glass 54 thru which the level of the oil within the reservoir may be observed at all times.

I claim:

1. A cooling unit for cooling liquids comprising a refrigerating unit, a cooling compartment, a tubular evaporator projecting from said refrigerating unit into said cooling compartment with a section of said tubular evaporator exposed between said refrigerating unit and means for directing a continuous flow of the liquid to be cooled into and out of thermal contact with the exposed portion of the evaporator for precooling.

2. A cooling unit for cooling liquids comprising a refrigerating unit including a tubular evaporator, a cooling compartment, said evaporator being partially mounted within and partially without said cooling compartment, means for directing a continuous flow of the liquid to be cooled into and out of thermal contact with the exposed portion of the evaporator, a vessel for collecting the liquid pre-cooled by said evaporator, said vessel being adapted to be mounted within said cooling compartment to be additionally cooled with its liquid contents by the evaporator section located with said cooling compartment.

3. A cooling unit for cooling liquids comprising a refrigerating unit including an evaporator, a cooling compartment mounted in spaced relation to said refrigerating unit, said evaporator extending from said refrigerating unit into said cooling compartment, a water cooling apparatus suspended above the evaporator between said refrigerator unit and said cooling compartment to have the liquid to be cooled pass over said water cooling apparatus onto and around said evaporator, a vessel for collecting the pre-cooled liquid below said evaporator, said vessel being adapted to be mounted in said cooling compartment to additionally cool the liquid contained therein by the remainder of said evaporator.

4. A cooling unit for cooling liquids comprising a refrigerating unit having a single tubular evaporator, a cooling compartment, means for directing a stream of the liquid into thermal contact with a portion of said evaporator and means for collecting and storing the pre-cooled liquid in the cooling compartment for cooling by the remainder of said evaporator.

5. A liquid cooler for precooling and final cooling of liquids, a cooling compartment, a tubular evaporator projecting into said cooling compartment with a portion of it located on the outside of the compartment and means for directing a continuous flow of the liquid into and out of thermal contact with the evaporator on the outside of said cooling compartment.

6. A liquid cooler for precooling and final cooling of liquids, a cooling compartment, a tubular evaporator projecting into said cooling compartment.

ment with a portion of the evaporator on the outside of the compartment, a water cooler on the outside of said compartment and associated and arranged with the evaporator to have a continuous flow of the liquid to be cooled flow over the water cooler into and out of thermal contact therewith and have said water cooler direct the

liquid into and out of thermal contact with said evaporator.

7. A liquid cooler as set forth in claim 6 with means associated with said evaporator for collecting the precooled liquid after leaving said evaporator. 5

MAXWELL R. KARGE.
